WALTER J. BRASSINGTON, OF BROOKLYN, NEW YORK, AND WILLIAM B. BURTNELL, OF NEW YORK, N. Y.

Letters Patent No. 65,869, dated June 18, 1867.

IMPROVED METHOD OF SUPPLYING LOCOMOTIVE TENDERS WITH WATER.

The Schedule referred to in these Letters Patent and making part of the same.

TO ALL WHOM IT MAY CONCERN:

Be it known that we, WALTER J. BRASSINGTON, of Brooklyn, county of Kings, State of New York, and WILLIAM B. BURTNELL, of the city of New York, in the county and State of New York, have invented a Method of Supplying Tanks of Locomotive Tenders with Water; and we do hereby declare that the following is a full, clear, and exact description thereof, reference being had to the accompanying drawing, making a part of this specification, in which—

Figure 1, sheet 1, is a side elevation of a locomotive engine and tender, showing the application of our invention thereto.

Figure 3, sheet 2, is a front end elevation of the tender, showing its tank and feed-water apparatus.

Figure 2, sheet 1, is a top view of fig. 1.

Figure 4, sheet 2, is a diametrical section of a reservoir to be used in very deep wells.

Figure 5, sheet 2, is a side view of a coupling which is used in attaching the feed or supply pipe to the tender.

Similar letters of reference indicate corresponding parts in the several figures.

This invention relates to a new and improved mode of supplying water to the tanks of locomotive-engine tenders, whereby the use of pumps, elevated reservoirs, and other expensive machinery, requiring the attendance of persons at different points along a road, are dispensed with, and the tanks supplied with less loss of time and labor than attends the use of pumps.

The nature of our invention consists in a tender-tank of a locomotive made air-tight, and provided with a pipe communicating with the locomotive boiler, and also with a device for attaching a pipe which is designed to lead into a reservoir or well of water for the purpose of supplying said tank with water; this arrangement being such that steam from the boiler may be employed as the means for creating a vacuum in the tender-tank when it is desirable to have water flow into the said tank; our invention further consists in the combination of a secondary air-tight water-tank with a spray pipe, and with a primary tank; our invention consists, further, in an auxiliary vessel or vessels in combination with the air-tight tender-tank of the locomotive, whereby water may be supplied from deep wells or deep places, or from elevated positions.

To enable others skilled in the art to understand our invention, we will describe one mode of carrying it into effect.

The mode which has been most generally adopted for supplying water to the tanks of locomotive tenders, is to have elevated reservoirs located at proper points along a road, which are supplied with water by means of forcing-pumps, and from which water is drawn by means of pipes leading into the said tanks. This mode involves considerable expense, loss of time, and labor, and should long detention of a train upon a road, from accident or other cause, deprive the tank of water, no means have been provided for elevating water should it be near at hand. It is contemplated by our invention to supply an engineer with means whereby he can rapidly supply his tank with water from a river, stream, pond, or other reservoir of water situated near the road.

In the accompanying drawings, A represents the boiler of a locomotive engine, and B the tender thereof. This tender is provided with a tank, C, which is constructed in the usual manner, with the exception that this tank is made air-tight for all practical purposes, so that a vacuum can be produced in it by the introduction of steam from the boiler A. The pipe a leads from the boiler to the tank, and has a cock, a¹, applied to it, by which the engineer can let on or cut off steam at pleasure. A short pipe or connection, b, is applied to the tank C, having a cock, c, and also a hooked fastening, d, applied to it. The outer end of this short pipe is adapted for receiving a coupling, d', upon one end of a hose or flexible pipe, D, shown in figs. 3 and 5, which latter has ears, e e, projecting from its coupling d', for receiving the hooks on fastening d, and thus securing the coupling in place. If desirable, a packing-ring may be applied on the outer end of pipe b, for making a tight joint when the coupling d' is held in its place by the hooked fastening. The flexible hose is made of suitable length to reach the water in a well or reservoir, as shown in fig. 1, and on its lower end a strainer, S, may be applied, for preventing the entrance of foreign substances into the tank of the tender. In practice extra sections of hose will be provided, in case one section should not be long enough to reach into the water of the well or reservoir, as the case may be. A smaller cool-water vessel, E, is employed for allowing of the introduction of

water into the tank C through the spray pipe f, for suddenly condensing steam in said tank. The vessel E can be supplied with water from tank C by forcing steam into this vessel through pipe a², and then opening a communication between the tank and vessel by means of the cock which is applied to pipe t. To supply water to the tank C, one end of the hose pipe D is applied to the nozzle of pipe b, and the other end of this pipe immersed in water, as indicated in fig. 1. The cock e is closed and the cock a¹ opened, thus allowing steam from boiler A to rush into the tank. The cock a¹ is then closed and the steam in the tank allowed to condense and form a vacuum therein, after which the cock e is opened, when water from the well will instantly rush into the tank and fill the said space. The hose pipe D is then detached and stowed away upon the tender, and the engineer is ready to proceed on his journey. When water is not found in sufficient quantities near the surface of the ground, and a deep well is required to obtain it, we contemplate employing either an elevated reservoir, or one which is applied within the well, in connection with the air-tight tender-tank. In the latter instance we use an air-tight reservoir, G, shown in fig. 4, which is provided with a pipe, K, leading down from the upper end of this reservoir into the water. The water is first elevated into this reservoir by introducing steam from the boiler A into it, through a pipe, G', thus producing a vacuum which will cause the water from the well to rise through pipe K and supply this vacuum. The water thus elevated is then forced into the tank C through pipe H and a flexible hose section, in the manner above described for obtaining water which is near the surface of the ground. It will be found necessary to employ a valve, J, constructed substantially as shown in fig. 4, in conjunction with the reservoir G, for automatically closing the steam inlet instantly the steam is cut off from this reservoir. Such valve is opened by the outward pressure of steam under its enlarged portion, and it is closed again by the recoil of the spring which is applied to its upwardly-projecting stem, as shown. The reservoir G is applied permanently in the well from which water is to be drawn, and located as near the top of the well as practicable.

We are aware that it has been essayed to supply the tanks of locomotive tenders with water by the force of steam from the boiler of a locomotive acting directly upon a column of water which is confined in an apparatus arranged within a well. Should such method succeed practically it would involve considerable expense, and would not place in the hands of an engineer of a locomotive engine the means and power of supplying the tank of the tender with water whenever it was found necessary. Such method, if practicable at all, would involve the expense of a peculiarly-constructed contrivance located within a well at every "watering-place," and provided with valves which would be liable to derangement, and consequently not certain in their action at all times; besides which, there would be a great loss of steam by condensation in consequence of bringing it in direct contact with the cool water in the well. We avoid objections incident to some of the devices to effect the desired object, by making the tank-tender air-tight, forming a communication between it and the locomotive boiler, and providing it with a hose which will lead down into the water wherever water is found convenient. Our invention will also be found useful for facilitating the flow of water into tank-tenders when the water is drawn from elevated reservoirs.

We do not confine ourselves to the particular construction of the parts herein shown and employed, as their construction may be varied without departing from the spirit of our invention. In practice it will be desirable to have a branch pipe provided with a cock, extending from the steam pipe a to the short pipe b, for the purpose of introducing steam into the lifting pipe D, to expel the air after this pipe has been introduced into water. This will prevent the air which was in pipe D from being carried into the tender-tank when the cock e is opened.

Having described our invention, what we claim as new, and desire to secure by Letters Patent, is—

1. An air-tight tender-tank of a locomotive engine, provided with a pipe communicating with the locomotive boiler, and also with devices for attaching a pipe which is designed to lead into a reservoir or well of water, for the purpose of supplying said tank with water, substantially as described.
2. The combination of the secondary air-tight water-tank E, and its spray pipe f, with the primary tank C, substantially in the manner and for the purposes described.
3. The arrangement, with an air-tight tender-tank C, and pipes a and D, of reservoir G, which is constructed to operate substantially as specified.
